FLOOR RACK FOR REFRIGERATOR CARS

Charles S. Johnston, Glencoe, Ill., assignor to
Transportation Specialties Company, Chicago,
Ill., a corporation of Illinois

Application March 26, 1938, Serial No. 198,289

12 Claims. (Cl. 105—375)

The present invention relates to floor racks for refrigerator cars, and is particularly concerned with the provision of improved metal floor racks which are adapted to be used in refrigerator cars to support the freight in such manner as to permit the free circulation of the cooling air about the load in a manner similar to that accomplished by wooden floor racks, but with a greater freedom of ventilation.

One of the objects of the invention is the provision of an improved floor rack construction for refrigerator cars which is completely fireproof and which is adapted to provide a maximum freedom of ventilation or air movement through the floor racks for the purpose of effecting a cooling or refrigeration of the products supported upon the floor rack.

Another object is the provision of an improved floor rack for refrigerator cars which is firm, sturdy, and rigid, and provided with a maximum amount of free air openings, and which can be constructed economically so that the invention may be placed within the means of a larger number of users of refrigerator cars.

Another object of the invention is the provision of an improved floor rack construction which utilizes a minimum amount of structural metal or other materials, but which provides air ventilation channels underneath the rack and openings through the rack for a maximum amount of ventilation, without sacrificing strength.

Another object of the invention is the provision of different forms of refrigerator floor rack structure, each of which is adapted to provide a maximum amount of ventilation, but all of which are firm and rigid so that they are adapted to support the heaviest loads which might be placed upon them without deformation or damage, even when the refrigerator car is subjected to hard jolts or rough usage in traffic.

Another object of the invention is the provision of an improved refrigerator car floor rack structure which is adapted to be provided with a substantially plane or smooth upper surface so as to permit the greatest freedom for rolling traffic, and which is also provided with ventilation apertures, without any substantial waste of the material of which the covering sheet is constructed.

Other objects and advantages of the invention will be apparent from the following description and the accompanying drawings, in which similar characters of reference indicate similar parts throughout the several views.

Referring to the five sheets of drawings accompanying this specification,

Fig. 1 is a horizontal sectional view, taken through a refrigerator car, just above the floor racks, showing the floor racks in plan;

Fig. 2 is a top plan view of one form of construction of the floor rack, such as, for example, one of the four small racks which are used adjacent the car doors;

Fig. 3 is a vertical sectional view, taken on the plane of the line 3—3 of Fig. 2, looking in the direction of the arrows, showing the details of structure;

Fig. 4 is a vertical sectional view, taken on the plane of the line 4—4 of Fig. 2, looking in the direction of the arrows;

Fig. 5 is a plan view of one of the other larger floor racks, four of which are used at each end of the car, as shown in Fig. 1, this figure being on a smaller scale, and having the major portion of the top covering removed;

Fig. 6 is a vertical sectional view, taken on the plane of the line 6—6 of Fig. 5, looking in the direction of the arrows;

Fig. 7 is a vertical sectional view, taken on the plane of the line 7—7 of Fig. 5, looking in the direction of the arrows;

Fig. 8 is a view similar to Fig. 5 of another modified form of floor rack;

Fig. 9 is a vertical sectional view, taken on the plane of the line 9—9 of Fig. 8, looking in the direction of the arrows;

Fig. 10 is a vertical sectional view, taken on the plane of the line 10—10 of Fig. 8, looking in the direction of the arrows;

Fig. 11 is another top plan view of a modification;

Fig. 12 is a vertical sectional view, taken on the plane of the line 12—12 of Fig. 11, looking in the direction of the arrows;

Fig. 13 is a vertical sectional view, taken on the plane of the line 13—13 of Fig. 11, looking in the direction of the arrows;

Fig. 14 is a fragmentary plan view of another form of the invention;

Fig. 15 is a vertical sectional view, taken on a plane extending longitudinally of the floor rack of Fig. 14; Fig. 16;

Fig. 16 is a vertical sectional view, taken on a plane extending transversely of the floor rack of Fig. 14;

Fig. 17 is a fragmentary sectional view, taken on a plane at right angles to one of the stringers of Fig. 4, showing a modified form of stringer construction;

Fig. 18 is an enlarged sectional view taken through the frame members of the type of Fig. 4.

Referring to Fig. 1, 20 indicates in its entirety the refrigerator car, which is shown diagrammatically as being provided with side walls 21, 22, end walls 23, 24, and bulkheads 25, 26 dividing the car into the central space for the freight, and the two ice compartments 27, 28 located at each end of the car.

The cars are usually provided with the centrally located and opposite doorways 29 and 30, and the floor racks are preferably arranged as shown in the plan view of Fig. 1.

In order that the car may be used for other purposes, without floor racks on the floor, which is indicated by the numeral 32, the floor racks are preferably pivotally mounted so as to be folded up against the side walls of the car. Thus the four racks 33-36 are pivotally mounted by means of hinges 37, so that the racks 33 and 34 fold up against the wall 21 and the racks 35 and 36 against the wall 22. Suitable latching or securing devices are provided to hold the racks in fixed position against the walls or to engage the frame members of the racks along the middle of the car so as to take the thrust when the racks tend to slide along the floor, instead of placing all of the load upon the hinges 37.

The racks 33-36 thus cover one end of the car, while similar racks 38-41 cover the opposite end of the car. The space between the doorways 29, 30 is preferably covered by four small racks 42-45, which are of sufficient size to fill this space. Each of these racks is preferably pivotally mounted on the adjacent one of the other larger racks, such as, for example, the rack 43 is pivotally mounted by hinges to the rack 33, the rack 45 to the rack 35, the rack 44 to the rack 41, and the rack 42 to the rack 39, as shown.

Referring now to Figs. 2 and 3, the framework 40 of the rack there shown, such as, for example, the rack 43 of Fig. 1, preferably comprises a plurality of metal stringers 46 and channelled frame members 47, also of metal, extending transversely to the stringers, a covering of expanded metal 48, and an external frame at the top made of angles 49-52.

The stringers and channelled members may be made of sheet metal of suitable thickness, such as, for example, 18 gauge material; but I desire it to be understood that the thickness of the material will be dependent upon the particular service for which the cars are equipped, and heavier or thinner sheet metal may be used. The gauge metal selected for an example is believed to be of sufficient strength to handle the majority of different loads.

The stringers 46 preferably each have a vertically extending body flange 53 and a horizontally extending foot flange 54 at right angles thereto. The stringers are only slightly shorter than the top of the rack is wide, and the depth of the body flange 53 may correspond to the depth of the present frame members used under floor racks, or it may be varied to change the amount of ventilation.

Each of the stringers 46 is provided with a multiplicity of apertures 55, which may be arranged as shown in Fig. 4, in two rows, with the apertures staggered for the purpose of providing cross ventilation through the stringers, which in the example of Fig. 2 will extend longitudinally of the car.

The foot flanges 54 may be oppositely arranged with the two centrally located stringers 46, and

they are preferably turned outwardly at the outermost stringers 46, as shown in Fig. 3.

The stringers are provided with a multiplicity of vertically extending slots 56, located in the upper edge of the body 46, the slots being of the same thickness as the gauge of metal of which the channelled frame members 47 are constructed. The slots 56 are deep enough in Fig. 4 to receive the channelled members 47 when these members are slightly straightened out by the slots, which involves making the slots slightly deeper than the normal depth of the channel.

Referring to Fig. 4, the channelled members 47 in this embodiment may have a centrally located flat body 57 and a pair of diagonally extending flanges 58, 59, both turned toward the same side of the body flange 57 and extending at an angle of, for example, 45 degrees thereto.

In the embodiment of Fig. 2, four stringers are provided, and therefore the channelled members 47 are straightened out at the points 60-63, so that they may be received in the slots 56. By straightening out, I mean that the diagonal flanges 58 and 59 are brought into the plane of the body flange 57 of the channelled member 47 at the slot 56.

The channelled members 47 are a forced fit in the slots 56, and the stringers are arranged as shown in Fig. 3, with their body flanges 53 at right angles to the channelled members 47. The stringers may be welded to the channelled members at all of the points 60, 63 for each channelled member, if desired; but it may also be sufficient to merely weld one or two points on each channelled member or to select at random points on the channelled members and stringers for welding, care being taken so that each channelled member is preferably welded to at least one stringer.

Despite the flattening of the channelled members 47 at the points 60-63, the upper edges of the channelled members 47 and the upper edges of the stringers 46 are all brought into the same plane by the application of pressure to the points of juncture 60-63, and this provides a framework to which the expanded metal framework 48 can be secured.

The expanded metal framework 48 comprises a sheet of sheet metal of suitable gauge, which has been provided with a multiplicity of staggered slits and then expanded by force applied to the sheet transversely to the direction of the slits. This ordinarily leaves the metal at the junctures still extending slightly diagonally to the plane of the expanded sheet, but I prefer to subject the expanded sheet to rolling or pressure in some other form so that all of the metal is brought into the same plane. This provides an expanded metal sheet having a multiplicity of diamond shaped apertures 64 and a multiplicity of diagonally extending and transversely extending strips 65, 66. The expanded metal sheet for any rack is cut to the size of the rack desired and then applied to the top of the framework shown in Fig. 2, comprising the channelled members 47 and stringers 46.

In addition to these channelled members 47, the framework is preferably provided at each end of the stringers with one angle member 49 and 51, the angle member having a vertical flange 69 extending into the slot 56, and having its horizontal flange 70 brought into the plane of the upper edges of the stringers 46 and channelled members 47 to provide a border frame member for the rack.

The expanded metal sheet 48 may then be extended over the edges of the horizontal flanges 70 of the angles 49 and 51, and under these horizontal flanges, as shown at 71, the horizontally extending flanges projecting slightly beyond the ends of the stringers 46.

The other two sides of the rack, that is, the top and bottom of Fig. 2, may also be finished off by providing the angle members 50 and 52 (Fig. 2). For example, the angle member 52 (Fig. 3) has its vertical flange 72 welded to the ends of the channelled members 47 and has its horizontal flange 73 applied above the expanded metal 48 by welding afterwards. The adjacent stringer 46 is braced by means of a plurality of short channelled members 74, which fit in the corners of the stringers 46 and angle 52 and are welded at each end in the position shown in Fig. 3.

The angle 50 (Fig. 3) has its vertical flange 75 welded to the ends of the channelled members 47 and its horizontal flange 76 flush with the top edges of the stringers 46 and channelled members 47, and its horizontal flange is outwardly turned and located below the expanded metal 48.

A plurality of similar bracing members 77 extend between the foot 54 of the adjacent stringer 46 and the angle 59, to both of which they are welded.

It should be understood that the apertures 55 in the stringers may be made larger, and the heavier gauge metal employed, or the apertures may be made smaller and lighter gauge metal employed. The stringers may also be reinforced by flanging out the apertures 55 of the stringers, after the manner shown in Fig. 17.

Referring to Fig. 4 and Fig. 2, the endmost stringers 46 may be provided with metal hinge members 78, comprising pieces of sheet metal which are welded at 79 to the stringers, and which are provided with apertures 80 for a suitable pintle, thereby forming part of the hinges 37.

It should also be understood that while the stringers are preferably equally spaced from each other and the channelled members are preferably equally spaced from each other to provide the same kind of support under all parts of the expanded metal, they need not be equally spaced in every instance, and the spacing may be varied for particular purposes. More or less stringers or channelled members may also be employed.

Referring to Figs. 5 to 7, this is a modification. In this case the stringers, which have been indicated by the numeral 81, are of similar structure; except that the slots 82 are wider, to accommodate not only the body flange 83 of the regular channels 84, but also the transverse flanges 85 and 86 of those channels. The channels are placed on their sides in the slots 82, and preferably are a close fit within the slots, except for the two endmost channelled members 84 at the left and right of Fig. 7, and these two are welded in the corners provided in the stringers 81.

In this embodiment the framework is again preferably finished at the two ends by means of angle members 87, 88, and the expanded metal covering 48 may be applied above the complete framework, comprising stringers, channels, and angles, by welding, as described, and the extreme edges of the expanded metal may be turned downward, as at 89, on all of the sides of the rack. The downwardly turned edges 89 may be welded in place or may be held in proper position by virtue of their own stiffness.

Referring to Figs. 8 and 9, this is another

modification, in which the structure of the rack is similar to that of Figs. 2-4, but the slots 90 in the stringers 91 are of less depth so that only one of the diagonal flanges, that is, the flanges 59 of the channelled members 47, need be straightened out for insertion into the slots 90, as the upper flange 58 and part of the channelled members 47 project from the stringers 91.

The channelled members 47 are otherwise of the same construction as shown in Fig. 2, and the framework, comprising the channels 47 and stringers 91 welded together, is finished off by means of four angle irons 49-52, applied as described with respect to Figs. 2-4, with the horizontal flanges of the lateral angle irons 49 and 51 extending in opposite directions.

Fig. 18 is a full size sectional view of one of the channelled members 47. In this embodiment, like Fig. 5, the expanded metal covering 48 may extend over the edges of the angle irons 49-52 and may have its edge bent downward, as indicated by the numeral 89 on each side of the rack.

Referring to Figs. 11-13, this is another modification which is provided with wooden stringers for supporting the channelled members. In this case the frame of the floor rack comprises a plurality of wooden stringers 92 arranged like the metal stringers previously mentioned with respect to the channelled members 93, except that the channelled members are spaced from each other and supported by a plurality of Z-shaped sheet metal members 94 which serve as bearing plates, spacers, and frame members.

The Z-shaped bearing plates are provided with a flat body portion 95, which is preferably as wide as the top of the wooden stringer 92, with a depending flange 96, which engages the side of the stringer 92.

The upwardly extending flange 97 is provided with a plurality of slots 98, or is cut away at the ends to provide a place for the channelled members 93, which are arranged in the slots, and at the ends of the Z bar 94, engaging the body flange 95, to which the channelled members may be welded.

The Z bar 94 is provided with a plurality of apertures 99 for receiving the bolts 100, which also pass through apertures 101 in the stringers, thereby securing the stringers to the Z bars and channelled members.

In this case the upper and lower sides of the framework in Fig. 11 are finished by providing additional channelled members 102, 103, which, as seen in Fig. 12, are arranged with the side flanges extending outwardly, and with the body flange welded to the ends of the channelled members 93.

The expanded metal covering 48 may extend to the edges of the frame, comprising the outside channelled members 93, 102, and 103, or it may extend beyond the edges and be turned downwardly, as in the previous embodiments.

The metal parts in this construction are welded, whereas in the previous embodiments the stringers 92 are provided with slots or counterbores 104 for receiving the heads of the bolts 100.

Referring to Fig. 15, this is another modification, in which the stringers are made partly of wood and partly of angle irons. In this embodiment the stringers 105 are again equally spaced, and are each provided with an angle iron member 106, which is secured to the stringer by the wooden bolts 107, the heads of which are embedded in the stringers.

The vertical flange 108 of each angle iron is

provided with a plurality of equally spaced slots 109, and the slots are adapted to receive a plurality of metal strips or bars 110, which may be made of sheet metal, and which are secured in the slots by a close fit and by welding. The end-most slots 109 are filled with the vertical flange of an angle iron 111 or 112 (Fig. 16), thereby providing a firmer frame member at the border of the rack, the horizontal flanges 111, 112 being flush with the top of the angles 106, which involves cutting down the vertical flange 108 by the thickness of the flange of the angles 111, 112 from the last slot to the end of the angle iron 106. The other end borders of the framework may be finished by providing additional angle irons 113, 114 (Fig. 15), the vertical flanges of which are welded to the ends of the bars 110, and the horizontal flanges of which are flush with the top edge of the flange 108.

In this case the expanded metal covering 48 may again be welded to the framework at a multiplicity of spaced points, preferably at intersections of the bars 110 and angle irons 106, since they are welded, and may secure the expanded metal covering to both of the transverse frame members.

The expanded metal covering may terminate flush with the outermost edges of the angle irons 113, 114, and it may be provided with a hair-pin bend 115 at each edge (Fig. 16) where it projects beyond the angle irons 111, 112.

In this embodiment the stringers 105 project beyond the framework at one side, as shown in Fig. 16, being provided with a cylindrical, curved end 116, and with an aperture 117 to receive a bolt used as a pintle for a hinge.

I desire it to be understood that any of the floor rack sections 33—36, 42—45, or 38—41 may be constructed according to any of the modifications, although the sizes shown indicate that the first modification of Figs. 2—4 was made to fit the rack sections at the doorway, and the other modifications were made of a size for the other positions.

Any of the modifications may be made of any size desired and may be located at any of the points in the car.

It will thus be observed that I have invented an improved floor rack structure which may be made completely of metal so that it is entirely fireproof, yet it may be made stronger than the floor racks of the prior art and may be so constructed that it has a greater capacity for ventilation.

The floor racks permit ventilation underneath the expanded metal covering in both directions, since the stringers may be provided with apertures, and the floor racks provide a maximum ventilation through the racks, since the frame occupies a minimum amount of space, and the expanded metal has a maximum amount of ventilating openings.

The floor racks constructed according to the present invention are also preferably galvanized over-all, after assembly of the metal parts, and this also tends to secure together those parts of the stringers, frame members and covering which may not have been welded. Thus the complete assembly is amply protected against rust, and the racks present a cleaner and more sanitary appearance.

The rack covering of expanded and pressed metal also provides a relatively smooth and bumpless surface for rolling traffic, such as trucks.

Due to the interlocking arrangement between the stringers and channelled members which constitute the frame, and the welding, the present floor racks have a maximum of strength and rigidity, and they may be constructed at a low cost, since their structure provides the strength and rigidity with a minimum amount of metal. The entire framework is further strengthened by the attachment and welding of the expanded metal to the framework, since the strips of metal in the expanded metal covering extend diagonally of the framework and act like braces.

While I have illustrated a preferred embodiment of my invention, many modifications may be made without departing from the spirit of the invention, and I do not wish to be limited to the precise details of construction set forth, but desire to avail myself of all changes within the scope of the appended claims.

I claim:

1. In a floor rack for refrigerator cars, the combination of a plurality of stringer members, with a plurality of frame members extending transversely to said stringer members, and located at the top of said stringer members, one of said members being provided with spaced slots for receiving a part of the other of said members, whereby the upper surfaces of both of said members may be arranged flush to provide a framework, and a foraminated covering member carried by said framework and secured thereto, said transverse frame members comprising a plurality of channelled members.

2. In a floor rack for refrigerator cars, the combination of a plurality of stringers, said stringers comprising horizontally extending foot flanges and vertical flanges, with a plurality of frame members, said frame members comprising channels, each channel having a body flange and a pair of diagonally extending edge flanges, said stringers having slots in their upper edges for receiving said channels, said channels being deformed at each slot for the insertion of the diagonal flanges into the slot, and a covering of expanded metal for the frame provided by said channelled members and stringers, said channelled members being flush with the upper edges of said stringers, and said expanded metal having all of its parts pressed into substantially the same plane.

3. In a floor rack for refrigerator cars, the combination of a plurality of metal stringers, each stringer having a vertically extending flange provided with a multiplicity of apertures and having a laterally turned foot flange, each stringer being provided with a multiplicity of slots in its upper edge for receiving a plurality of channelled members, said channelled members having a body flange and a pair of laterally extending flanges all arranged in said slots with the upper surfaces of said channelled members flush with the upper edges of said stringers, and a covering of expanded metal having all of its parts pressed into substantially the same plane.

4. In a floor rack for refrigerator cars, the combination of a plurality of metal stringers, each stringer having a vertically extending flange provided with a multiplicity of apertures and having a laterally turned foot flange, each stringer being provided with a multiplicity of slots in its upper edge for receiving a plurality of channelled members, said channelled members having a body flange and a pair of laterally extending flanges all arranged in said slots with

the upper surfaces of said channelled members flush with the upper edges of said stringers, and a covering of expanded metal having all of its parts pressed into substantially the same plane, said rack having similar channelled members arranged to form a border frame at the edges of said rack flush with the top of said stringers, and all of said parts being welded together at a plurality of spaced points.

5. In a floor rack for refrigerator cars, the combination of a plurality of stringers, each stringer having a body flange and a foot flange, and said body flange being provided with a multiplicity of ventilation apertures, with slots in the upper edge thereof, and a plurality of channelled members, said channelled members having part of the body thereof secured in said slots, and a covering of expanded metal having all of its parts pressed into substantially the same plane and secured to said channelled members in spaced relation to said stringers.

6. In a floor rack for refrigerator cars, the combination of a plurality of stringers, each stringer having a body flange and a foot flange, and said body flange being provided with a multiplicity of ventilation apertures, with slots in the upper edge thereof, and a plurality of channelled members, said channelled members having part of the body thereof secured in said slots, and a covering of expanded metal having all of its parts pressed into substantially the same plane and secured to said channelled members in spaced relation to said stringers, said stringers also supporting angle irons at the borders of said rack, and said covering extending over said angle irons.

7. A floor rack for railway cars comprising a plurality of stringers consisting of metal angle irons having the vertical flanges thereof provided with a multiplicity of apertures and having a multiplicity of aligned slots at the upper edge thereof, and a plurality of transverse frame members carried by said slots and secured therein in spaced relation to each other, said frame members comprising channels, the channels having a vertical flange, and a pair of horizontal flanges, the horizontal flanges being deformed at each of said slots, to permit said channels to be secured in said slots, and a foraminated metal covering carried by said stringers and transverse frame members and secured thereto at a multiplicity of spaced points.

8. A floor rack for railway cars comprising a plurality of metal stringers, each stringer having a horizontal flange and a wider vertical flange, said vertical flange being provided with a multiplicity of apertures, and having at its upper edge a multiplicity of spaced slots, the slots of the respective stringers being in alignment, and a plurality of channelled transverse frame members having a vertical flange, and a pair of horizontal flanges, and said horizontal flanges being of substantially the same width as said slots, whereby said channelled members may be located and secured in said slots flush with the top of said stringers, and a foraminated metal covering carried by said transverse frame members and stringers and secured thereto at a plurality of spaced points.

9. In a floor rack for railway cars, a plurality of angle iron stringers having a horizontal flange and a wider vertical flange, said vertical flange being provided with a plurality of apertures and having at its upper edge a plurality of spaced

slots, with a plurality of transverse channelled frame members, said transverse channelled frame members having a body flange and a pair of diagonally extending edge flanges, said slots being of sufficient width to receive said body flange, and one of said edge flanges being deformed at said slots in said stringers whereby the transverse frame members may be inserted in said slots and secured therein, and a foraminated metal covering carried by the other edge flanges of said transverse frame members.

10. In a floor rack for refrigerator cars, the combination of a plurality of stringers comprising sheet metal members having horizontal bearing flanges and vertically extending supporting flanges, said vertically extending supporting flanges being provided with a multiplicity of regularly spaced slots arranged in series, one slot in each of said stringers being aligned with slots of the same series in other stringers, and a plurality of transverse frame members, said transverse frame members having a vertical flange and diagonally bent flanges, said diagonally bent flanges being bent into the plane of said vertical flange at each of said slots whereby said horizontal frame members may be received and secured in said slots, an external frame comprising a plurality of angle iron members secured to said transverse frame members to form a boundary frame, a covering of expanded metal lath having all of its parts in substantially the same plane, fixedly secured to said horizontal frame members and boundary frame, and bracing means extending from the outermost of said stringers to said boundary frame.

11. In a floor rack, the combination of a plurality of sheet metal stringers, each stringer having a relatively broad vertically extending body flange and having a transversely extending foot flange for increasing its bearing on the floor of a refrigerator car, said stringers being spaced at predetermined distance from each other and being provided at their upper ends with initially open slots of substantially rectangular shape and a plurality of channelled members, each channelled member having a vertical web and a pair of horizontally extending flanges carried by the web, said channelled members being disposed in said slots substantially flush with the top edge of said stringers, and a foraminated covering carried by the upper edges of said stringers and the upper surface of the top flanges of said channelled members, said foraminated covering comprising expanded metal having substantially all of its parts pressed into substantially the same plane, the stringers and channelled members and expanded metal being welded together at predetermined points.

12. In a floor rack, the combination of a plurality of sheet metal stringers, each stringer having a relatively broad vertically extending body flange and having a transversely extending foot flange for increasing its bearing on the floor of a refrigerator car, said stringers being spaced at predetermined distance from each other and being provided at their upper ends with initially open slots of substantially rectangular shape and a plurality of channelled members, each channelled member having a vertical web and a pair of horizontally extending flanges carried by the web, said channelled members being disposed in said slots substantially flush with the top edge of said stringers, and a foraminated covering carried by the upper edges of said stringers and the

upper surface of the top flanges of said channeled members, said foraminated covering comprising expanded metal having substantially all of its parts pressed into substantially the same plane, the stringers and channeled members and expanded metal being welded together at predetermined points, the said stringers extending

longitudinally of the car and having a plurality of relatively large openings formed therein at regularly spaced points for permitting a transverse circulation of air through the stringers as well as circulation in the spaces between the stringers.

CHARLES S. JOHNSTON.
